LOG CLASSIFYING MACHINE

Karl Lennart Birger Johansson, Jonkoping, Sweden; assignor of part interest to Gunnar Gideon Edstrom, Jonkoping, Sweden

Application October 3, 1951, Serial No. 249,433

Claims priority, application Sweden
December 12, 1950

6 Claims. (Cl. 198—38)

1

In saw mills and other places for collecting logs, such as saw logs, pulp wood and props, the logs have to be classified according to thickness, length, quality or other grounds. This is a time wasting and trying work when executed by hand.

One object of the invention is to provide a mechanical device for classifying logs which is simple in construction, effective in operation and time saving. Another object is to provide such a device which operates substantially automatically and delivers the classified lumber at different collecting stations in such a way that it is dropped and thereby can easily be collected on rail vehicles or trucks.

With these and other objects in view the invention will be hereinafter fully described and illustrated by way of an example in the accompanying drawing in which:

Fig. 1 is a side elevation, partly in section, of a device according to the invention.

Fig. 2 is a vertical sectional view along line II—II in Fig. 1.

A number of carriages 1 for transport of individual logs to a plurality of delivery stations are provided with a shaft 2 with two wheels 3. Two U-shaped guide rails 4 extend along parallel closed paths in vertical planes with the flanges directed towards each other, and the wheels are located between the flanges in each rail. As shown in the drawing the rails are composed each of two horizontal portions and two half-circular end portions. Each carriage is connected with the adjacent carriage by means of a coupling member formed by a tube 5 in which another tube 5a is telescopically introduced so that the distance between the carriages may vary as required when the carriages pass along the end portions of the rails. The tube 5 is fixed to the shaft of a carriage whereas the tube 5a is hingedly connected with the shaft of the adjacent carriage so that the carriages are connected to a chain.

Two downwardly directed arms 6 are fixed one at each end of the shaft 2, and two similar arms 7 are fixed to a transverse frame portion 8 having its ends connected by frame portions 8a with the arms 6, to which they are fastened. The frame portion 8 rests upon and is secured to the tube 5 so that each carriage forms a rigid construction for transport of a log.

At the lower ends of the arms 7 the one ends of two log carrying members 9 are hingedly provided, while the other ends rest on falling latches 10, which are pivotally mounted on the arms 6 and are operated by rods 12 for the release of

the carrying members 9. The upper ends of the rods 12 are hingedly connected with levers 14, extending from sleeves secured to a transverse shaft 13, and by turning the shaft the falling latches 10 release the carrying members 9 simultaneously. The shaft 13 is further at one end provided with a hub for a release lever 15 and an alignment arm 16 by means of which the hub, which is not rotatable on the shaft, can be adjusted in lateral direction. The adjustment is performed by a slide 17 having a handle 18.

Along one of the guide rails 4 a number of fixed release shoulders 19 are mounted, one for each delivery station comprising a collecting truck 20, and the shoulders are displaced laterally from each other in such a way that the release lever 15 when adjusted in a certain position strikes only a corresponding shoulder 19, whereby the log is dropped into the desired collecting truck.

The logs to be classified are fed individually in their length direction on an endless conveyor 21 to a carriage placed in front of the conveyor which is mounted somewhat inclined. The log passes over the carrying members 9 and between the arms 6 and 7 to a log receiver 22 comprising an endless belt 23 driven by chains from a motor 24. Stationary side walls 25 are provided to keep the log in position on the endless belt.

The conveyor 21 and the log receiver are mounted on a common frame 27 hingedly supported at one end by a bolt 26, whereas the other end rests on a hydraulic jack 28, by means of which the frame can be raised and lowered.

The receiver 22 is tiltingly mounted on a shaft 34 in bearings supported by the frame 27, and Fig. 2 shows the receiver in a horizontal end position. Normally, however, the receiver is tipped by its gravity to the other end position, in which it rests against a stud 35. In this sloping position the upper portions of the endless belt 23 and the conveyor 21 are substantially parallel to each other.

The log is thus pushed on to the belt 23 until the point of gravity has passed the vertical line through the shaft 34, whereupon the receiver turns over to its horizontal end position and the log is released from the conveyor 21. At the same time the motor 24 may be stopped manually or by any known device not shown in the drawing. By the hydraulic jack 28 the frame 27 is now lowered, whereby the log is delivered upon the carrying members 9, and as the conveyor 21 is mounted on the same frame it is simultaneous-

ly lowered and does not form any obstacle for the log.

The whole chain of carriages is now fed a step by means of another hydraulic jack 29, the piston rod 30 of which being provided with a feeding tooth 31 cooperating with studs 32 on the shafts 2.

As soon as the log is transferred from the conveyor 21 to a carriage the operator determines the diameter or other quality of the log and adjusts the release arm 15 into a position on the shaft 13 which corresponds to the one of the shoulders 19 which is situated at the desired delivery station where the log is to be dropped. The chain of carriages is thereafter moved a step by means of the hydraulic jack 29. When the carrier in this or a subsequent step arrives at the selected station, the carrying members are released. From his place at the receiving carriage the operator may manually start and stop the conveyor 21 and the endless belt 23, and he can also control both hydraulic jacks 28, 29 and thus attend to the operation of the whole classifying device.

I claim:

1. A log classifying device, comprising a guide rail carrier extending along a closed path, a number of carriages supported by and movable along said guide rail carrier for the transport of individual logs to a plurality of delivery stations, said carriages having log carrying members extending in the travelling direction of the carriages and adapted to be released by a falling latch, a conveyor for feeding individual logs in their length direction transversely to said path and over the carrying members of a carriage while supported by a lower portion of said guide rail carrier and being placed in front of said conveyor, a number of fixed release shoulders provided along said path one for each delivery station and displaced laterally from each other, a laterally adjustable release lever on each carriage connected with said falling latch and adapted to cooperate with a selected one of the release shoulders, and means for conveying said carriages along said guide rail carrier.

2. A log classifying device, comprising a guide rail carrier extending along a closed path, a number of carriages supported by and movable along said guide rail carrier for the transport of individual logs to a plurality of delivery stations, said carriages having log carrying members extending in the travelling direction of the carriages and adapted to be released by a falling latch, a conveyor for feeding individual logs in their length direction transversely to said path and over the carrying members of a carriage while supported by a lower portion of said guide rail carrier and being placed in front of said conveyor, a vertically adjustable log receiver mounted in front of said conveyor and extending in its upper position between and above two carrying members of said carriage so as to deliver the log upon the carrying members when lowered, a number of fixed release shoulders provided along said path one for each delivery station and displaced laterally from each other, a laterally adjustable release lever on each carriage connected with said falling latch and adapted to cooperate with a selected one of the release shoulders, and means for conveying said carriages along said guide rail carrier.

3. A log classifying device, comprising a guide rail carrier extending along a closed path, a number of carriages movable along said guide

5 rail carrier for the transport of individual logs to a plurality of delivery stations, said carriages having log carrying members extending in the travelling direction of the carriages and adapted to be released by a falling latch, a conveyor for feeding individual logs in their length direction transversely to said path and over the carrying members of a carriage while supported by a lower portion of said guide rail carrier and being placed in front of said conveyor, a vertically adjustable log receiver mounted in front of said conveyor and extending in its upper position between and above two carrying members of said carriage so as to deliver the log upon the carrying members when lowered, said log receiver having its log supporting portion formed as an endless conveyor, a number of fixed release shoulders provided along said path one for each delivery station and displaced laterally from each other, a laterally adjustable release lever on each carriage connected with said falling latch and adapted to cooperate with a selected one of the release shoulders, and means for conveying said carriages along said guide rail carrier.

25 4. A log classifying device, comprising a guide rail carrier extending along a closed path, a number of carriages movable along said guide rail carrier for the transport of individual logs to a plurality of delivery stations, said carriages having log carrying members extending in the travelling direction of the carriages and adapted to be released by a falling latch, a conveyor for feeding individual logs in their length direction obliquely upwards over the carrying members of a carriage placed in front of said conveyor, a vertically adjustable log receiver mounted in front of said conveyor and extending in its upper position between and above two carrying members of said carriage so as to deliver the log upon the carrying members when lowered, said log receiver having its log supporting portion mounted 30 tiltable from a position parallel to said conveyor to a substantially horizontal position, a number of fixed release shoulders provided along said path one for each delivery station and displaced laterally from each other, a laterally adjustable release lever on each carriage connected with said falling latch and adapted to cooperate with a selected one of the release shoulders, and means for conveying said carriages along said guide rail carrier.

40 5. A log classifying device, comprising two guide rails having U-formed sections and extending along two vertical, closed and parallel paths, a number of carriages movable along said guide rails by means of wheels running between the flanges of the rails for the transport of individual logs to a plurality of delivery stations, said carriages being connected one to another by means of coupling members and having log carrying members extending in the travelling direction of the carriages and adapted to be released by a falling latch, a conveyor for feeding individual logs in their length direction transversely to said path and over the carrying members of a carriage while supported by a lower portion of said guide rails and being placed in front of said conveyor, a number of fixed release shoulders provided along said paths one for each delivery station and displaced laterally from each other, a laterally adjustable release lever on each carriage connected with said falling latch and adapted to cooperate with a selected one of the release shoulders, and means for conveying said carriages along said guide rails.

6. A log classifying device, comprising a guide rail carrier extending along a closed path, a number of carriages movable along said guide rail carrier for the transport of individual logs to a plurality of delivery stations, said carriages having log carrying members extending in the travelling direction of the carriages and adapted to be released by a falling latch, a conveyor for feeding individual logs in their length direction transversally to said path and over the carrying members of a carriage while supported by a lower portion of said guide rail carrier and being placed in front of said conveyor, a vertically adjustable log receiver mounted in front of said conveyor and extending in its upper position between and above two carrying members of said carriage so as to deliver the log upon the carrying members when lowered, said conveyor and said log receiver

being mounted on a common frame hingedly supported at one end and resting on a lifting jack at the opposite end, a number of fixed release shoulders provided along said path one for each delivery station and displaced laterally from each other, a laterally adjustable release lever on each carriage connected with said falling latch and adapted to cooperate with a selected one of the release shoulders, and means for conveying said carriages along said guide rail carrier.
